UNITED STATES PATENT OFFICE.

JOSHUA J. JONES, OF PITTSBURGH, PENNSYLVANIA, ASSIGNOR, BY MESNE ASSIGNMENTS, TO UNION DRAFT GEAR COMPANY, A CORPORATION OF ILLINOIS.

FRictional-Resistance Device.

1,129,297.

Specification of Letters Patent. Patented Feb. 23, 1915.

Application filed December 9, 1908. Serial No. 466,301.

To all whom it may concern:

Be it known that I, JOSHUA J. JONES, a citizen of the United States, residing at Pittsburgh, in the county of Allegheny and 5 State of Pennsylvania, have invented new and useful Improvements in Frictional-Resistance Devices, of which the following is a specification.

This invention relates to frictional resistance devices, and more particularly to friction draw-gear and buffing apparatus for railway service.

One object of my invention is to provide an improved construction of the above character of compact design and adapted to be cheaply manufactured.

Another object of my improvements is to provide a friction draw-gear and buffing apparatus having a plurality of frictional resistance devices adapted to act successively in taking up draft and buffing strains.

In the accompanying drawing; Figure 1 is a side elevation, partly in section, of a friction draft rigging for a railway car, embodying my improvements; Fig. 2 a top plan view of same, with one of the friction blocks removed; Fig. 3 a transverse section thereof taken on the line *a—a* of Fig. 1; and Fig. 4 a perspective view of one of the friction blocks.

According to a preferred construction, as illustrated in the drawing, I provide a draw bar 1 having a series of oppositely arranged notches 2, the inclined faces of which are adapted to coact with corresponding faces of friction blocks 3. Each pair of friction blocks 3 is adapted to move laterally against the resistance of a coil spring 4 which may be held in engagement with one friction block 35 by means of a bolt 5 passing through the opposite blocks of a pair, as shown in the drawing, or by means of a strap passing around the outside of the blocks, as shown in my prior Patent No. 618417 of January 31, 1899. The draw bar 1 is provided with slots 6 of sufficient extent to permit of a certain longitudinal movement of the bolts 5 therein.

I have shown a series of three sets of friction mechanisms, in which the outer friction mechanisms are arranged to normally bear against fixed abutments 7 suitably secured to the center sills 9 of the car. The draw bar 1 is supported on a friction plate 8 fastened to the under portion of the center sills 9.

55 In operation, a pull on the draw bar 1 causes

its longitudinal movement to the left and consequently the friction blocks 3 at the extreme left ride up on an opposite pair of inclined faces of the notch 2, against the resistance of spring 4. Frictional resistance to the movement of the draw bar is thus produced and in addition the lateral movement of the friction blocks causes frictional engagement between the abutment 7 and the vertical faces of the blocks. The longitudinal movement 60 of the draw bar continuing, the second or intermediate pair of friction blocks are carried by the draw bar into engagement with the first pair of friction blocks and thereupon the first set of blocks act as an abutment for 65 the intermediate set and cause this set to ride up the corresponding inclined surfaces. By this means the frictional resistances due to the intermediate friction mechanism is added to that of the first and the resistance 70 to longitudinal movement of the draw bar is correspondingly increased. In like manner, the friction mechanism at the extreme right is finally brought into engagement with the intermediate friction blocks by the 75 continued longitudinal movement of the draw bar, so that the frictional resistance of the three friction mechanisms is finally brought into action. In buffing, it will be apparent that a similar successive operation 80 of the friction mechanisms takes place, in this case, the friction mechanism at the right being the first to be operated, then the intermediate mechanism, and finally the one at the extreme left.

It will now be seen that a simple friction device has been provided whereby a gradually increased resistance is interposed to the movement of the draw bar, according to the force of pulling or buffing impact to be 85 transmitted and absorbed.

Having now described my invention, what I claim as new and desire to secure by Letters Patent, is:—

1. In a friction draw-gear and buffing apparatus, the combination with a draw-bar, of a plurality of yielding resistance mechanisms mounted on the draw-bar and spaced apart each comprising opposing laterally movable friction blocks, a coacting wedge on 100 the draw-bar and a spring for resisting the lateral movement of the blocks and stops for 105 successively limiting the longitudinal movement of said mechanisms to cause the successive serial action of said yielding resistance 110

mechanisms upon longitudinal movement of the draw-bar.

2. In a friction draw-gear and buffing apparatus, the combination with a draw-bar, 5 of a plurality of yielding resistance mechanisms carried by the draw-bar and adapted to successively oppose longitudinal movement of the draw-bar and comprising opposing laterally movable blocks having inclined 10 friction faces, a longitudinally movable wedge on the draw-bar having correspondingly inclined friction faces, and a spring for resisting lateral movement of the blocks, said blocks also being provided with friction 15 faces transverse to the line of draft and adapted to coact with corresponding friction faces upon lateral movement thereof.

3. The combination with a draw-bar provided with a series of oppositely arranged 20 notches, of laterally movable friction blocks carried in said notches and adapted to have a longitudinal movement with the draw-bar and springs longitudinally movable with said friction blocks for resisting the lateral 25 movement of said blocks.

4. In a friction draw-gear and buffing apparatus, the combination with a draw-bar provided with pairs of oppositely arranged inclined friction faces, of friction blocks 30 having friction faces adapted to coact with said inclined friction faces, a spring for resisting lateral movement of each pair of op-

posite friction blocks, and means for causing the successive action of the several pairs of blocks.

5. In a friction draw-gear and buffing apparatus, the combination with a draw-bar provided with pairs of oppositely arranged notches, of laterally movable friction blocks adapted to be carried in said notches, springs 40 for resisting lateral movement of opposite friction blocks, and means for causing the serial lateral movement of the successive pairs of friction blocks, to thereby resist the longitudinal movement of the draw-bar.

6. In a friction draft gear, the combination with a draw-bar, of a plurality of yielding resistance mechanisms mounted on the draw-bar and spaced apart, a fixed abutment for opposing longitudinal movement of one 50 resistance mechanism upon longitudinal movement of the draw-bar, said resistance mechanism operating as a stop for preventing longitudinal movement of the next succeeding resistance mechanism upon a predetermined longitudinal movement of the draw-bar.

In testimony whereof I have hereunto set my hand.

JOSHUA J. JONES.
